PURPLE MARTIN BIRD HOUSE

Arthur E. Vail, Griggsville, Ill., assignor to Trio
Manufacturing Company, Griggsville, Ill.

Filed Feb. 5, 1970, Ser. No. 21,276

Term of patent 14 years

Int. Cl. D30—01

U.S. Cl. D30—3

Fig. 1

Fig. 2

FIG. 1 is a perspective view of a purple martin bird house illustrating my new design;

FIG. 2 is a top plan view of said bird house;

FIG. 3 is a side elevational view of said bird house;

FIG. 4 is a bottom plan view of said bird house;

FIG. 5 is a front-on elevational view of said bird house. The elevational view from the side opposite that shown in FIG. 3 is the same as FIG. 3. The elevational view from the side opposite that shown in FIG. 5 is the same as FIG. 5.

I claim:

The ornamental design for a purple martin bird house, substantially as shown and described.
